(57) **CLAIM**

The ornamental design for a bottle as shown and described.

DESCRIPTION

FIG. 1 is a perspective view of a bottle;

FIG. 2 is a left side elevation view of the bottle, the right side elevation view being a mirror image of the left side elevation view;

FIG. 3 is a front elevation view of the bottle;

FIG. 4 is a rear elevation view of the bottle;

FIG. 5 is a top plan view of the bottle; and,

FIG. 6 is a bottom plan view of the bottle.

The broken lines show portions of the bottle and form no part of the claimed design.
